UNITED STATES PATENT OFFICE.

HIRAM R. HARDING, OF BALTIMORE, MARYLAND, ASSIGNOR TO THE HARDING
PEELING MACHINE COMPANY, INC., OF BALTIMORE, MARYLAND, A CORPORA-
TION OF MARYLAND.

JOINTLESS WOVEN-WIRE BELT CONVEYER.

Application filed April 11, 1921. Serial No. 460,199.

To all whom it may concern:

Be it known that I, HIRAM R. HARDING, a citizen of the United States, residing at 37 S. Liberty Street, Baltimore, in the county of Baltimore City and State of Maryland, have invented certain new and useful Improvements in Jointless Woven-Wire Belt Conveyers, of which the following is a specification.

This invention relates to conveyers of the continuous belt type which may be employed for transferring goods from one place to another within factories, warehouses and stores, or may constitute the conveyer belt portion of an organized mechanism.

The main purpose of my invention is to provide a conveyer belt of woven wire which shall be light in weight while possessing great tensile strength.

In the following description I shall refer to the accompanying drawings which illustrate one form thereof and wherein Figure 1 is a side elevation of one end of a woven wire belt conveyer embodying my invention, the drum or pulley being partly broken away; Fig. 2 is a fragmentary transverse sectional view of the same taken on the line 2—2 of Fig. 3; and Fig. 3 is a fragmentary top plan view of the woven wire conveyer belt.

It has heretofore been proposed to construct wire belts of wire by making each mesh of the belt of separate short pieces of wire connected to the adjoining mesh sections by a link joint, so that each mesh section would be pivotally connected to its neighbors. Such linked mesh constructions are used largely for the wire supporting web of beds and couches but they do not have sufficient tensile strength to serve as conveyer belts.

I conceived the idea of constructing conveyer belts of interwoven steel wire wherein the longitudinal wire strands are continuous throughout the belt. It is known, however, that a wire which is frequently bent back and forth will very soon crystallize and finally break. I was enabled to successfully construct and use a conveyer belt with continuous longitudinal steel wire strands only after I made the discovery that crystallization could be avoided by making the pulleys or drums over which the belt runs of such a pitch diameter that the curvature of the pe-

riphery is less than the bend which will cause 55 a permanent set in the wire. In other words the wire must not be curved or bent beyond its elastic limit when passing over the surface of the drum or pulley. The diameter of the drum or pulley required for a wire of 60 any given size or gauge may be determined with sufficient accuracy by bending a piece of the wire through arcs of different curvature and noting the radius of the sharpest curve over which the wire may be bent without losing 65 its power to spring back when released. There is a critical curve for each size of wire having the same characteristics, over which it may be bent without exceeding its elastic limit and when bent to a greater extent it 70 loses its power of springing back and becomes permanently set. This elastic property of the steel wire which causes it to spring back or straighten out as soon as it has left the end drums, gives my continuous 75 steel-strand belt the inherent property of tending to maintain the upper and lower reaches of the belt in parallel planes, free from kinks or waves, so that the belt is substantially taut throughout its extent. 80

Having determined the proper diameter of the drum for any given wire, it will be evident that the wire is never curved or bent permanently or beyond its elastic limit when passing thereover and consequently the 85 molecular structure of the wire is not altered. In other words, a conveyer constructed in this manner does not cause a crystallization or otherwise impair the integrity of the wire strands and consequently the full tensile 90 strength of the wire is available.

My conveyer belt is formed of continuous lengths of steel wire 5 extending lengthwise and constituting the warp of the belt and cross wires 6 woven alternately over and 95 under the wires 5 and spaced the same distance apart thereby forming squares throughout the belt. Every third cross-member is preferably double, as indicated at 6'. At each side, the ends of the cross-wires are bent around a wire cable 8. Sprocket chains 10 extend outside and parallel with the cables and at suitable distances are provided with links having integral ears or lugs 10^a, which are perforated to receive 105 the double prongs of clips 12, by which the cables are secured to the chain. I prefer to electrically weld the prongs to the lugs 10^a,

as indicated at 14, so that they become, in effect, an integral part of the lugs. The chains, cables and woven wire are thus united into a unitary structure, which therefore combines the tensile strength of the continuous wire strands 5, the cables 8 and the sprocket chains 10.

The drums or pulleys at either end of the conveyer belt are provided upon either side 10 with sprocket teeth 15 to engage the links of the sprocket chains. The central body portion 17 of the drums may be constructed of sheet metal supported upon transverse ribs or bars 18 which are carried at either end by 15 flanges 19 projecting inwardly from the rims of the spider rings 20. The body portion or cylinder 17 of the drum extends outwardly somewhat from the base of the sprocket teeth 15, the parts being so positioned that the tension wires 6 will be on a median line through the links, as indicated in Fig. 2 to thereby cause the strains and stresses throughout the several parts of the conveyer to be equalized.

25 I have stated that the longitudinal warp wires 5 are continuous throughout the belt. In case the conveyer is longer than the wires which can be obtained, the meeting ends of different sections can be made continuous 30 by electric welding. The enormous loads which may be carried by conveyer belts constructed in accordance with my invention will be appreciated by engineers. The ten-

sile strength of steel wires is very great even for wires of very small guage or diameter 35 and by reason of the combined tensile strength of the plurality of wires the carrying capacity of the belt is very large in proportion to its weight per square foot. Furthermore, the cables and sprocket chains 40 augment the carrying capacity quite materially.

I claim:—

1. A belt conveyer, comprising a belt having a plurality of continuous parallel steel 45 wires extending longitudinally thereof, transverse wires interwoven with said longitudinal wires, continuous wire cables upon either side of the belt to which said transverse wires are secured, and drums over 50 which the belt passes having a cylindrical surface of less curvature than that which causes a permanent set in the said wires.

2. A belt conveyer, comprising a belt having a plurality of continuous parallel steel 55 wires extending longitudinally thereof, transverse wires interwoven with said longitudinal wires, continuous wire cables upon either side of the belt to which said transverse wires are secured, sprocket chains extending parallel with said cables having 60 means for securing the cables thereto at intervals throughout the length of the conveyer.

In testimony whereof I affix my signature. 65
HIRAM R. HARDING.
